Inventor:

John William Wright

By Mac Wallace White

ATTY.

UNITED STATES PATENT OFFICE.

JOHN WILLIAM WRIGHT, OF OLDSHAM, ENGLAND.

APPARATUS FOR CONTROLLING TRAINS ON RAILWAYS.

1,165,054.

Specification of Letters Patent. Patented Dec. 21, 1915.

Application filed July 14, 1915. Serial No. 39,787.

To all whom it may concern:

Be it known that I, JOHN WILLIAM WRIGHT, a subject of the King of Great Britain and Ireland, residing at 134 Manchester street, Oldham, in the county of Lancaster, England, have invented new and useful Improvements in or Relating to Apparatus for Controlling Trains on Railways, of which the following is a specification.

This invention relates to apparatus for controlling trains on railways and has special reference to apparatus of the kind wherein a ramp arranged at the side of the track in conjunction with a signal and raised and lowered into and out of operative position simultaneously with or independently of the raising and lowering of the signal, is adapted, in the event of over-running of the signal, to be engaged by a vertically movable rod mounted on the engine, which rod is thereby actuated and cuts off the steam and also operates the brake valve to apply the brakes.

The present invention comprises improved apparatus of the kind referred to.

According to my invention I employ a ramp having a long and a shorter ramp parts or surfaces adapted in operation to be engaged by two vertically movable rods mounted on the engine and I so arrange said surfaces and rods that the rod which co-acts with the shorter ramp part or surface comes into operation and is actuated to at once completely cut off the steam before the other rod comes into operation with, and is gradually operated by, the longer ramp part or surface to gradually apply the brakes.

I will fully describe my invention with reference to the accompanying drawing wherein—

Figure 1 is an elevation and Fig. 2 a plan illustrating my improved apparatus in the lowered or inoperative position. Fig. 3 is an end view of Fig. 1 and Fig. 4 is an elevation showing the apparatus in the raised or operative position.

Referring to the drawing, *a* is a ramp having two ramp parts or surfaces *b* and *b*¹ one of which, *b*, is considerably shorter than, and projects at its lower or front end beyond, the other *b*¹. The ramp *a* is supported by arms *c* pivoted to it and to brackets *d* mounted on the sleepers or otherwise suitably disposed at the side of the

track. The ramp is adapted to be raised and lowered in conjunction with or independently of the signal by suitable operating means which may be duplicated in order that the ramp may be actuated from either the signal cabin in front of or the cabin beyond it. Conveniently the operating means may comprise lifting levers *e*, *e*¹, links *f*, *f*¹, rods *h*, *h*¹, bell-crank levers *j*, *j*¹, links *k*, *k*¹, and hand levers *m*, *m*¹. The link *f* is directly connected to the lifting lever *e* and the link *f*¹ operates the lifting lever *e*¹ through the medium of a lever *n*.

With the parts or surfaces *b* and *b*¹ of the ramp *a* are adapted to co-act vertically movable rods *o* and *p* respectively mounted on the engine and provided at their lower ends with anti-friction rollers. The rod *o* which co-acts with the shorter part or surface *b* is connected to the slotted arm of a bell-crank lever *q* the other arm of which has pivoted to it one end of a link *r*. The other end of the link *r* is curved and slotted to co-act with a pin *s* on the steam regulator lever *t*. The upper end of the rod *p* which co-acts with the longer ramp part or surface *b*¹ and is arranged behind the rod *o*, is pivoted to the slotted arm of a lever *u* the other arm of which is pivoted to one end of a link *v* curved at its other end which is slotted to co-act with the handle of the brake valve lever *w*.

In operation the rods *o* and *p* co-act with the ramp parts or surfaces *b* and *b*¹ whereby they are actuated, and, through the levers *q* and *u* and links *r* and *v*, operate the regulator lever *t* and the brake valve lever *w* to cut off the steam and apply the brakes.

Owing to the arrangement of the ramp parts or surfaces *b* and *b*¹ and the rods *o* and *p*, the rod *o* co-acts with and is actuated by the part or surface *b* before the rod *p* co-acts with and is operated by the part or surface *b*¹. By this means the steam regulator lever *t* is fully operated and the steam completely cut off at once but the brake valve handle *w* is gradually operated and the brakes are gradually applied and are not fully applied until the roller on the rod *p* has traversed the full length of the ramp part or surface *b*¹. The slotted ends of the links *r* and *v* allow of the independent operation of the steam regulator lever and the brake valve lever.

By only partially raising the ramp *a* it can be set to partially cut off steam and apply the brakes and so reduce the speed of

an engine or train without bringing same to a standstill.

What I claim as my invention and desire to secure by Letters Patent is:—

- 5 1. In apparatus for controlling trains on railways, the combination of a ramp adapted to be raised and lowered in conjunction and simultaneously with the signal; a short ramp surface on said ramp; a long ramp surface 10 on said ramp; a movable rod mounted on the engine adapted to co-act with said short ramp surface, when raised, and to be at once fully operated thereby; means connecting said rod with the steam regulator; a second 15 movable rod mounted on the engine adapted to co-act with said long ramp surface and to be gradually operated thereby; and means connecting said second rod with the brake valve.
- 20 2. In apparatus for controlling trains on railways, the combination of a ramp adapted to be raised and lowered in conjunction and simultaneously with the signal; a long ramp part on said ramp; a movable rod 25 mounted on the engine adapted to co-act

with and be gradually operated by said ramp part; means connecting said rod with the brake valve; a short ramp part on said ramp projecting at its lower or front end beyond said long ramp part; a second movable rod 30 mounted on the engine adapted to co-act with and be fully operated by said short ramp part before the first rod is operated by said long ramp part; and means connecting said second rod with the steam regulator. 35

3. In a ramp for controlling trains on railways and adapted to be raised and lowered in conjunction and simultaneously with the signal, the combination of a long ramp part and a short ramp surface arranged 40 alongside said long ramp part and projecting beyond the same at its lower or front end.

In testimony whereof I have signed my name to this specification in the presence of 45 two subscribing witnesses.

JOHN WILLIAM WRIGHT.
